CLAIM

I claim the ornamental design for a lighting fixture, as shown and described.

DESCRIPTION

FIG. 1 is a rear perspective view of a lighting fixture showing a first embodiment of my new design.

FIG. 2 is a side view thereof, the opposite side being a mirror image thereof.

FIG. 3 is a top view thereof.

FIG. 4 is a bottom view thereof.

FIG. 5 is a rear perspective view of a lighting fixture showing a second embodiment of the claimed design.

FIG. 6 is a side view thereof, the opposite side being a mirror image thereof.

FIG. 7 is a top view thereof; and,

FIG. 8 is a bottom view thereof.

The broken line portions shown in FIGS. 1 and 5 are included to show environmental subject matter only and form no part of the claimed design.
